CLAIM

The ornamental design for a roller stamp, as shown and described.

DESCRIPTION

FIG. 1 is a front side elevation view of a roller stamp, showing our new design with the cap, and the rear side elevation view being a mirror image thereof;

FIG. 2 is a left side elevation view thereof, the right side elevation view being a mirror image thereof;

FIG. 3 is a top plan view thereof;

FIG. 4 is a bottom plan view thereof;

FIG. 5 is a front-left side perspective view thereof;

FIG. 6 is a front side elevation view of the roller stamp of FIG. 1 shown without the cap, and the rear side elevation view being a mirror image thereof;

FIG. 7 is a left side elevation view thereof, the right side elevation view being a mirror image thereof;

FIG. 8 is a top plan view thereof;

FIG. 9 is a bottom plan view thereof; and,

FIG. 10 is a front-left side perspective view thereof. The broken lines immediately adjacent the claim depict the
